C. YEOMANS

SEWAGE EJECTOR SYSTEM

Filed Dec. 19, 1925

Patented Aug. 3, 1926.

1,594,483

UNITED STATES PATENT OFFICE.

CHARLES YEOMANS, OF CHICAGO, ILLINOIS, ASSIGNOR TO YEOMANS BROTHERS COMPANY, OF CHICAGO, ILLINOIS, A CORPORATION OF ILLINOIS.

SEWAGE-EJECTOR SYSTEM.

Application filed December 19, 1925. Serial No. 76,461.

The present invention relates to periodically operating ejector systems for sewage and the like, in which a receptacle having an inlet and an outlet for sewage controlled by check valves, is connected to an air vent when the level of the liquid therein is low, and to a compressed air supply when the level is high, so that the sewage or the like alternately flows into the receptacle and is discharged therefrom.

In some such systems compressed air is employed not only to empty the ejector receptacle periodically but also, under control of a pilot valve actuated by a float in the receptacle, to operate the automatic valves that effect the admission and venting of air to and from the receptacle. Such an arrangement insures certainty of automatic operation and permits the disposition of most of the automatically moving parts, including any electric switches, in case the plant is electrically driven, some distance above the pit in which the ejector receptacle is placed, so that they are readily accessible for lubrication, inspection, and the like, and are not subject to the conditions prevailing in the ejector pit. But such systems, while well suited for large installations, are somewhat complicated and expensive since they require a constant source of compressed air including a storage tank, a pump for supplying compressed air thereto and means, such as an electric switch, automatically controlled by the air pressure in the tank for starting and stopping the driving motor of the pump.

The present invention seeks to provide a system suitable for small installations, which, while possessing many of the advantages of the system above referred to, is simpler and less expensive, and which avoids the necessity of a constant source of compressed air. To this end, the air pump or compressor is directly connected to the ejector receptacle and means actuated by an independent source of fluid under pressure, preferably the city water supply, is employed to control the starting and stopping of the pump and the venting of air from the receptacle, such fluid pressure means being in turn controlled by the level in the receptacle. The invention further consists in the features of improvement hereinafter set forth, illustrated in the preferred arrangement in the accompanying drawing,

and more particularly pointed out in the appended claims.

In the drawings:—

Fig. 1 is a view in elevation, with certain parts shown in section, of the improved system.

Fig. 2 is a sectional view of one form of air pump or compressor that can be employed.

The ejector receptacle 10 may be of any suitable construction. It is arranged as usual in a pit 11 below the floor level 12. In the form shown the receptacle is provided with an inlet pipe 13 for the sewage or the like, and with a discharge outlet pipe 14, these pipes being provided with suitable cut-off and non-return check valves 15 and 16. As the sewage or the like flows into the receptacle through the inlet pipe 13, air is vented therefrom through a pipe 17 connected to its upper end and extending upwardly therefrom. When the receptacle is full, air under pressure is admitted preferably through the pipe 17, to force the contents of the receptacle through the outlet or discharge pipe 14.

To effect the alternate venting of air from the receptacle and the admission of compressed air thereto, the pipe 17 in the preferred form shown, is connected at its upper end to an air exhaust pipe 18 provided with a vent valve 19 and to a compressed air inlet pipe 20 that is directly connected to an air pump 21. The air pump may be of simple rotary type, such as shown in Fig. 2, and comprising a rotor 22 mounted on a shaft 23 and provided with spring-pressed wing pistons or vanes 24, the pump shaft being directly connected to the shaft 25 of an electric motor 26.

Fluid pressure means are provided for controlling the closing and opening of the vent valve 19 and the starting and stopping of the pump motor 26, and preferably, as shown, separate fluid pressure devices of simple form are employed. Each of these devices comprises a casing 27 connected to a pipe 28 and provided with a diaphragm 29. The diaphragm of one of the devices is connected to the stem 30 of the vent valve 19 and the diaphragm of the other device is connected to a rod 31 which actuates a pilot switch 32. Springs 33 and 33' on the valve stem 30 and the rod 31 normally hold the vent valve and pilot switch open. The pilot switch is connected in circuit with a solenoid

switch 34 which serves to close and open the circuit of the motor 26.

The operation of the fluid pressure devices is under control of a float actuated 5 pilot valve 35. Preferably, as shown, the pilot valve is arranged within a suitable casing 36 mounted on a bracket 37 on the upper end of the ejector receptacle 10, and connected to the city water supply by a 10 pipe 38 provided with a cut-off valve 39. The casing is also connected to the pipe 28 that extends to the fluid pressure devices and to an exhaust pipe 40 which, in the 15 form shown, leads to the inlet pipe 13 of the ejector receptacle.

The stem 41 of the pilot valve 35 has a pin and slot connection with one arm of a bell crank lever 42 pivotally mounted on the bracket 37. The other arm of the lever has 20 a pin and slot connection with a float rod 43 extending upwardly through a stuffing box 44 in the top of the receptacle 10. In the form shown, the float rod is provided with an open bottom bell 45 at its upper end 25 and with an open top bell 46 at its lower end.

When the valve 35 is in the position shown in the drawing, it connects the fluid pressure devices to the exhaust pipe 40 so that the 30 diaphragms and springs of these devices will hold the vent valve 19 and the pilot switch 32 open. Under these conditions the pump is idle and air escapes through the pipe 17 and vent valve 19 to permit the flow 35 of sewage or the like by gravity in the receptacle. When the receptacle is filled, air trapped in the upper bell 45 lifts the float rod and shifts the valve 35 to connect the fluid pressure devices to the city water supply. 40 Vent valve 19 and pilot switch 32 are then closed and, under these conditions, the pump operates to supply air under pressure through the pipes 20 and 17 and thereby forces the contents of the receptacle out. 45 through the discharge pipe 14. When the receptacle is nearly emptied, liquid trapped in the lower bell 46 will return the pilot valve to the position shown in the drawings, so that the springs of the fluid pressure devices open the vent valve and pilot switch 50 and so stop the pump and permit the venting of air from the receptacle as it is again filled. Preferably, to hold the pilot valve in one or the other of its positions the bell crank lever 42 is provided with a weight which, as the valve is moved, shifts to one side or the other of a dead center position.

With the present improved system the 60 automatic controlling devices can be of simple, inexpensive form. For the most part such automatic devices and the electric switches can be located outside of the ejector pit and the necessity of providing a continuous supply of compressed air is avoided. 65 Obviously, changes may be made in the de-

tails set forth without departure from the scope of the invention as defined in the claims.

I claim as my invention:—

1. In combination in an ejector system 70 for sewage and the like, a receptacle having an inlet and an outlet provided with check valves, an air pump directly connected to said receptacle for forcing liquid therefrom and means actuated by fluid 75 pressure independent of the pump and controlled by the level in the receptacle for starting and stopping the pump and for controlling the venting of air from the receptacle. 80

2. In combination in a periodically operating 85 ejector system for sewage and the like, a receptacle having an inlet and an outlet provided with check valves, an air pump directly connected to the receptacle for forcing liquid therefrom, fluid pressure means controlling the starting and stopping of the pump and the venting of air from the receptacle, and float valve means actuated by the high and low levels 90 in the receptacle and adapted to control a source of fluid pressure independent of the pump to thereby effect the operation of said fluid pressure means. 95

3. In combination in a periodically operating 100 ejector system for sewage and the like, a receptacle having an inlet and an outlet provided with check valves, an air pump directly connected to said receptacle for forcing liquid therefrom, a fluid pressure device, means controlled thereby for starting and stopping the pump, a float 105 controlled by the liquid level in the receptacle and a valve mechanically actuated by said float and adapted to control a source 110 of fluid pressure independent of the pump to thereby effect the operation of said fluid pressure device. 115

4. In combination in a periodically operating 120 ejector system for sewage and the like, a receptacle having an inlet and an outlet provided with check valves, an air pump connected directly to said receptacle for forcing liquid therefrom, a valve controlling the venting of air from the receptacle, a fluid pressure device for intermittently closing and opening said valve, a float controlled by the liquid level in the receptacle and a valve mechanically actuated by said float and arranged to control a source of fluid pressure independent of the pump to thereby effect the operation of said fluid pressure device. 125

5. In combination in a sewage ejector system, 130 a receptacle having an inlet and an outlet provided with check valves, an air pump directly connected to the receptacle for forcing liquid therefrom, a valve controlling the venting of air from the receptacle, and means actuated by fluid pressure 135

independent of the pump and controlled by the level of liquid in the receptacle for starting and stopping the pump and for closing and opening the vent valve.

- 5 6. In combination in a periodically operating ejector system for sewage and the like, a receptacle having an inlet and an outlet provided with check valves, an air pump directly connected to the receptacle
- 10 for forcing liquid therefrom, a valve for controlling the venting of air from the receptacle, fluid pressure means for starting and stopping the pump and closing and opening said vent valve, a float controlled
- 15 by the liquid level in the receptacle and a valve mechanically actuated by said float and adapted to control a source of fluid pressure independent of the pump to thereby

effect the operation of said fluid pressure means. 20

- 7. In combination in a periodically operating ejector system, a receptacle having an inlet and an outlet provided with check valves, an air pump directly connected to the receptacle for forcing liquid therefrom, 25 a valve controlling the venting of air from the receptacle, fluid pressure devices for starting and stopping the pump and for closing and opening said vent valve respectively, and a float valve actuated by the high and low levels in the receptacle arranged to simultaneously connect and disconnect said fluid pressure devices to and from a source of fluid pressure independent of the pump. 30

CHARLES YEOMANS.
